ARCH-CORRECTIVE SHOE

William M. Scholl, Chicago, Ill.

Application January 10, 1936, Serial No. 58,457

3 Claims. (Cl. 36—71)

My invention relates to shoes for foot-corrective purposes, and has for its general objects to provide a novel and desirable shoe-construction especially suitable for use in the relief of weak or fallen arches, and which may be made by an efficient and advantageous method.

Sufferers with painful arch-conditions commonly wear what I may term "stock" arch-supports in "stock" shoes, in seeking relief, and even where only one foot is so affected it is common practice to wear such appliances in both shoes, to avoid the uneven effect or "limp" in walking that annoyingly results from wearing only one. One of the more specific objects of my invention is to so construct my improved shoes that wearing of a single arch-support is accommodated with little or no such uneven effect.

By "stock" shoes, as herein referred to, I allude to ready-made leather ones, internally contoured for good fit upon a normal foot of the size for which the shoe's length and width are indicated by conventional standards; and what I term "stock" arch-supports are suitably stiffened or padded appliances (of which various specific constructions are commercially available) to be loosely inserted in the user's shoes and to be positioned therein, in use, by coaction with the shoe and the foot; such an appliance being shaped in plan outline to underlie the foot's width from a line just back of the ball of the foot to the rear of the heel's under-surface, and the waist of the appliance having its inner side widened and arched upward, conformably with the curvatures of the foot's longitudinal arch. Such appliances commonly run in sizes marked with the standard lengths and widths of corresponding shoe sizes; but while such "stock" arch-supports are commonly thinned at the forward edge to meet the shoe's insole as smoothly as possible, and while the lacing or buttoning arrangement of the shoe's upper will accommodate considerable variation in the arch-depth of the appliance at its waist without discomfort or making the shoe unsightly, the heel portion of the appliance, upon which its proper positioning in the shoe and its cooperative relation to the foot quite largely depend, is customarily of substantial thickness for requisite stiffness and durability (a thickness of about .125 of an inch being a reasonable commercial average), so that the wearer's heel is lifted in the shoe materially above the level for which the contouring of the "stock" shoe is intended, with resultant disadvantages.

Even when "stock" shoes and arch-supports are simultaneously bought, difficulties in fitting

such shoes, with the appliances in place, not infrequently result in conditions that militate seriously against the user's comfort; against the slightly appearance of the footwear, and even against best functioning of the appliances to give the desired foot-relief; and more specific objects of my invention are to provide my improved shoes in a normal condition for sale that makes them fittable, regardless of whether or not "stock" arch-supports are to be worn therein, exactly as a corresponding-size of "stock" shoes would be; that gives them advantage in normally affording a certain amount of arch-supporting effect which tends to prevent occurrence of arch-troubles; and that permits of the substitution, at or after the time the shoes are purchased, of a "stock" arch support for the detachable "dummy" arch-supportive structure of either or both of the normal shoes, with minimal discomfort, shoe distortion, or other drawbacks.

Still another of my more specific objects is to provide in such shoes a construction that permits their production on the same lasts that are used in the making of corresponding sizes and styles of stock shoes, and that may, if desired, insure that any slight variation in the thickness of individual dummy arch-supports used in making up a quantity of the shoes, will not affect the internal contouring of the finished foot-wear.

To these ends, and for attaining other objects and advantages which will hereinafter become apparent, my improved shoes have their foundation-structures—i. e., the permanently-united sole, heel, and upper—normally supplemented by detachable "dummy" arch-supports or lifts, the upper surface of which forms part of the normal interior surface of the shoe that gives the lasted depth and internal contouring of a standard size of "stock" shoe; so that, when said dummy is removed, the foundation of the shoe affords an internal pocket or depression, throughout its heel and shank portions, wherein a "stock" arch-support may be inserted with but little, if any, undesirable effect on the fit, the appearance, or the comfort of the foot-wear. And, with respect to the manufacture of such shoes, the preferred structure herein set forth lends itself to production by a novel method that insures that the interior contouring of these special shoes of my invention, with the dummy arch-support in place, will exactly correspond with "stock" shoes of like last-sizes.

Further advantages of my invention will hereinafter become apparent from the following description, taken in conjunction with the accom-

panying drawing wherein I have shown one desirable embodiment of and practice of my invention, including various details from which variation may be made within the scope of the appended claims, but which I have found in practice to give desirable results.

In the drawing,—

Figure 1 is a perspective view showing, in conventionalized fashion, a shoe cut away in longitudinal section and having a "dummy" arch-support detachably secured in appropriate position therein; the visible part of said dummy having fragments broken away;

Fig. 2 shows in perspective a shoe-last suitable 10 for use in making the construction shown in Fig. 1, in association with a broken-away part of the "dummy"; and

Fig. 3 is a perspective view of a suitable "dummy", detached.

20 In the drawing, 10 indicates in general the permanent body or foundation of the shoe, conventionalized in the showing of its sole 11, shank 12, heel 13, and upper 14. As a matter of general styling appropriate for use in foot-relief cases, 25 the laced, oxford type herein shown is desirable, with the counter portion 15 of its upper well socketed and the top opening 16 of the upper well narrowed at its back, for snug, clinging engagement with the upper curves of the wearer's heel-30 protuberance.

18 indicates in general an arch-support "dummy", or removable lift, that normally is secured in place in the shoe body, and the top surfaces of which form part of the normal interior contouring of the merchantable shoe, giving it interiorly a "stock" shoe shape, substantially duplicating that of regular "stock" shoes of the same make and size.

This dummy, 18, simulates a stock arch-support in plan outline, and the depth or thickness of its 40 heel portion 19 and the tapered thinning of its forward edge 20 are in keeping with average practice in the manufacture of well-known stock arch-supports; the waist 21 of the dummy being preferably somewhat thinner than is customary 45 in "stock" arch-supports for the longitudinal arch of the foot and being preferably wholly of leather. A thin body of adhesive, 22, adjacent the forward edge of the dummy, may be used to secure it normally to the insole or sole-lining of the shoe, 50 for easy-enough removal on occasion.

The desirable construction of dummy 18 here shown comprises a pre-formed leather top piece 24, suitably arched and skived along the inner 55 side of its waist-portion 21, and with its heel-portion underlain by a reinforcing layer 25, which here is shown as a short metal heel-plate secured to the top piece by rivets 26. Desirably, the forward end of this plate has its inner corner 60 slightly arched upwardly, as at 27, this "corner hump" tending to prevent forward slipping of the foot in the shoe; to check any tendency of the wearer to rock to the inner side of the foot in walking; and to prevent displacement of the 65 scaphoid—just back of which the hump exerts its slight pressure.

For purposes having to do with a desirable procedure in making the shoes, the plate 25 is provided with a central tacking-opening 28.

70 In manufacture of my improved shoes, it is desirable to use the same lasts 30 on which stock shoes are made; the last shown in Fig. 2 being of conventional style having the usual heel-plate 31 to upset the points of the nails for the shoe-75 heel 13.

To give the added depth to the shoe being made, necessary to accommodate the proper dummy arch-support, that particular dummy arch-support which is to constitute a part of the finished shoe may be used, or a substantial counterpart of it; the appropriate "lasting-dummy" being tacked to the last and the shoe being lasted over it.

In practice, the amount of surplus upper-material that ordinarily is provided before the excess 10 is trimmed away in the manufacturing operation, is ample to accommodate the deepening of the permanent body of the shoe sufficiently to provide a dummy-receptive space or pocket A—A¹ throughout the heel and shank areas of the shoe, 15 so that, with the dummy in place, the full foot-reception depth A—B, and the last-contours, of the affected area are preserved; and a reduction of height of the shoe-heel 13 is desirably made, 20 to preserve a total height B—C at the rear of the shoe corresponding with the height of stock-shoe for which the naked last is designed.

It will be noted that where the identical "dummy" arch-support that is intended to be incorporated in the particular shoe being lasted is 25 utilized as the depth-increasing addendum to the last, its heel-plate 25 serves as a nailing plate in the manufacture of the shoe, to upset the ends of the heel-nails; and that such use of the 30 identical dummy insures that the internal contours of the completed shoe will conform with great precision to that of a stock shoe made over the naked last, so that no change from a favored 35 last and size is needed, on a customer's first requirement for arch supports.

In practice, the wearing of a "stock" arch-support in the pocket A—A¹ that is exposed upon removal of the "dummy" arch-support, not only goes very far to avoid discomfort to the wearer 40 and malformation of the shoe, whether worn in both shoes or only one; but also it reacts to further the effectiveness of the corrective appliance itself, particularly by minimizing any 45 tendency of the loosely-inserted stock appliance to work away from proper position in the shoe, and by avoiding that slight increase in pitch of the shank of the wearer's foot with respect to the ground which follows from the use of stock 50 arch-supports in stock shoes.

I claim:

1. An arch-corrective shoe adapted to permit the wearing, in either of a pair thereof, of a "stock" arch-support without materially lifting the affected portions of the user's foot with respect to the shoe-heel and producing a "limp" effect, comprising a permanent body having an internal pocket in its heel and shank portions and local to the area that is designed to underlie the foot's width from a line just back of the ball of the foot to the rear of the heel's undersurface, deepening said portions by a predetermined amount in excess of that required for normal foot-fitting, said pocket depth being throughout the stated area approximately the depth requirement of a "stock" arch-support that has a thinned 60 front edge and a thicker heel-portion; and a "dummy" arch-support normally located in but removable from said pocket and of shape and thickness conforming the shoe's interior depth and contouring to those which are normal to 65 foot-fitting, "stock" shoes.

2. An arch-corrective shoe adapted, when worn in pairs, to receive in either thereof without materially lifting the user's heel and producing a "limp" effect, a "stock" arch-support, comprising 75

- a permanent body having an internal depth in its portion receptive of the below-mentioned "dummy" that is greater than required for foot-fitting; and an arch-support "dummy" approximating at its front and rear ends the depth of average "stock" arch-supports and plan-contoured to approximately conform to foot-curvatures and to underlie the foot from just back of the ball thereof to the rear of the heel, said "dummy" being normally located in and filling said excess-depth space of said shoe body and detachably secured in place in said body as part of the merchantable shoe.
3. An arch-corrective shoe adapted, when worn in pairs, to receive in either thereof without materially lifting the user's heel and producing a "limp" effect, a "stock" arch-support, comprising a permanent body having an internal depth in its portion receptive of the below-mentioned "dummy" that is greater than required for foot-fitting; and an arch-support "dummy" approximating at its front and rear ends the depth of average "stock" arch-supports and plan-contoured to approximately conform to foot-curvatures and to underlie the foot from just back of the ball thereof to the rear of the heel, said "dummy" being normally located in and filling said excess-depth space of said shoe body and detachably secured in place in said body as part of the merchantable shoe, the forward edge of said "dummy" being skived to merge smoothly into the permanent sole of the shoe and its heel-portion being approximately .125 of an inch thick.

WILLIAM M. SCHOLL.
